PHILIP RAY COURSEY, OF RICHMOND, AND HUMFREY ANDREWES, OF LONDON, ENGLAND, ASSIGNORS TO DUBILIER CONDENSER CORPORATION, OF NEW YORK, N. Y., A CORPORATION OF DELAWARE

RECTIFYING DEVICE

Application filed July 5, 1928, Serial No. 290,392, and in Great Britain July 7, 1927.

This invention relates to an improvement in rectifying devices employing thermionic tubes and adapted to receive varying, intermittent, or alternating current and to supply a modified or rectified current to a work circuit.

An object of this invention is to provide means for improving the efficiency of rectifying devices by eliminating losses such as those present in transforming devices.

Another object of this invention is to supply the filament current and anode potential of thermionic tubes from an intermittent or an alternating current source of supply, modifying the values of such current by means of a capacitive unit without the necessity of using transforming devices.

An additional object of this invention is to lower the cost of making the devices disclosed by the substitution of a condenser for a transformer.

A further object of this invention is to provide an additional impedance means in circuit with a capacitive unit in a rectifying device to limit or prevent surges in such device.

In one embodiment of this invention the same has been applied to rectifying units such as those used in battery eliminators and, for a better understanding of this invention, reference is made to the accompanying drawing in which like reference numerals indicate the corresponding parts:

Fig. 1 of the drawing discloses a circuit employing certain features of this invention, and

Figs. 2 and 3 disclose modifications employing additional novel features.

In rectifying devices which are suitable for use in so-called battery eliminators or devices for supplying suitable energy to radio sets from alternating current supply mains, it is customary to employ either a double or a single wave thermionic rectifying valve supplied with the necessary filament current and anode potential from a small transformer.

It is well known, however, that with the small transformers used in such eliminators or devices, owing to the large ratio of the magnetizing current to the full load current

and to other factors, the efficiency of such transformers is usually low. As the actual power in watts required for energizing such a device may not be more than approximately 10 watts and, as such an arrangement using a transformer may require 100 or more watts, an improvement in the efficiency is highly desirable.

Referring to Fig. 1 of the drawing, an alternating current source of supply is shown impressed upon the mains 1 and 2 of a rectifying device embodying the principles of this invention. A conventional thermionic rectifying valve V is shown having a plate P and filament F. The filament F is connected across the mains 1, 2 and receives its energy therefrom. A condenser C' is inserted in series with the filament F, the impedance of the condenser serving to supply the necessary current to the filament F of the rectifying valve. While only one filament is shown it is obvious that a plurality of filaments, such as are commonly used in a double wave rectifying valve, may be employed. It is also evident that any desired means for further regulating the current flowing through the filament may also be used. It will also be recognized that a thermionic tube having three or more elements and employing a grid as indicated in Fig. 1 may be used in place of the two-element valve shown, and that this invention may be used to supply energy to the various thermionic tubes in any radio circuit in general as well as to the rectifying circuit shown. The capacity of the condenser C will have a fairly large value with the usual type of rectifying valve, as the filament current required may be of the order of 0.5 amperes. The power factor angle, however, of such condenser will be quite small and the losses in the same will be negligible. Therefore, the power consumed will be only that required to heat the filament.

The arrangement shown in Fig. 1 is particularly adapted for use with a relatively high voltage supply source and no transformer for the anode potential of the rectifying valve is necessary. Hence, a unit comprising a rectifying valve V and a condenser C' is all that is required to supply rectified

current for the anode potential of a radio set. In practice, however, a condenser such as C'' is bridged across conductors 3 and 4 to smooth out the rectified current obtained.

5 The circuit shown in Fig. 2 is particularly adapted for use with a source of alternating current supply of lower potential. In this case the condenser C' must be relatively larger, but the rectifying valve anode potential is raised by means of a small auto transformer having windings as indicated at L' and L''. Such auto transformer may be made very small as it has to supply only the rectified direct current energy which, with 10 the usual type of radio receiver, amounts to only one or two watts, hence the efficiency of the unit may be kept quite high.

Fig. 3 shows another feature of this invention which comprises the insertion of an additional impedance element in series with the 20 condenser C' for the purpose of limiting current surges due to the charging of the condenser when switching the same into or out of circuit. Preferably, this impedance is 25 made inductive since its current limiting characteristics are then opposite to that of the condenser. The value of the impedance may be relatively small. Such an impedance element may, of course, be used to advantage 30 in the circuits shown in Fig. 2.

For the purposes of illustration, this invention has been shown and described as applied to a rectifying device but, as many other and varied forms and uses will present themselves to those versed in the art without departing from the spirit of this invention, we do not wish to be limited either in structure or arrangement except as indicated by the terms and scope of the appended claims.

40 We claim:

1. In an electrical circuit containing a thermionic tube, a source of supply energy impressed upon the circuit, a filament of the tube connected to said source of supply, a 45 condenser in series with the filament circuit, and an impedance in circuit with said condenser.

2. An electrical circuit containing a thermionic tube, a filament of said tube connected 50 to a source of energy, a condenser in series with the said filament circuit and a choke coil in series with the condenser and adapted to reduce surges in the circuit.

3. In combination a rectifying device having 55 a thermionic rectifying valve, a smoothing condenser for the rectified impulses, and a condenser in series with the filament circuit of the said rectifying valve, and an impedance in circuit with the condenser.

4. A rectifier system comprising a tube 60 having filament and plate electrodes, the filament being adapted to be energized by a given voltage, means for connecting the filament to a source of current supply having a 65 voltage higher than that for which the fila-

ment is adapted, and a condenser connected in series with said filament across the input terminals of said rectifier system, for reducing the voltage of the supply current to the value for which the filament is adapted to be used.

5. An alternating current rectifier comprising a thermionic valve having filament and plate electrodes, means for connecting the filament to a source of alternating current power supply, a condenser connected in series with said filament to reduce the potential of the current supplied to the filament to a voltage for which the filament is adapted, 75 the plate supply circuit of the rectifier being 80 connected across the terminals of said condenser.

In testimony whereof we affix our signatures.
